UNITED STATES PATENT OFFICE.

LUTHER W. GRAYSON, OF YOUNGSTOWN, OHIO, ASSIGNOR OF ONE-HALF TO CHARLES G. RUNYEON, OF YOUNGSTOWN, OHIO.

TURBINE.

1,132,336.

Specification of Letters Patent. Patented Mar. 16, 1915.

Application filed October 30, 1914. Serial No. 869,386.

To all whom it may concern:

Be it known that I, LUTHER W. GRAYSON, a citizen of the United States, and a resident of Youngstown, in the county of Mahoning and State of Ohio, have invented a new and Improved Turbine, of which the following is a full, clear, and exact description.

My invention relates to turbines or rotary engines to be operated by any suitable fluid under pressure.

The object of the invention is to provide a simple, strong and efficient turbine of the reversible type, and which is easily controlled.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views, and Figure 1 is a vertical section of my invention on line 1—1, Fig. 2; Fig. 2 is a section on line 2—2, Fig. 1; Fig. 3 is a perspective view of the rotor; Fig. 4 is a perspective view of one of the impinging blades of the rotor; Fig. 5 is a plan view on the rotor; Fig. 6 is a side elevation of the turbine; and Fig. 7 is an elevation of my turbine provided with more than one fluid inlet.

Referring to the drawings, 8 represents the stator, which has two concentric, cylindrical sections 9 and 10 united in the central part of the facing lateral surfaces by a partition 11 forming an annular recess 12 at each end of the stator. The stator 8 is provided with an extension 13, forming a base therefor, and also with lateral flanges 14 at the edge of the outer cylindrical sections 10. Closing the ends of the stator 8 are covers 15 bolted to the flanges 14. The covers have annular projections 16 fitting into annular recesses 17 provided at the ends of the cylindrical section 9 of the stator 8. The annular recesses receive packing 18, which also engages the annular projection 16, and thus leakage is prevented from the annular chambers formed by the annular recesses 12 when the same are closed by the covers 15. Each of said annular chambers has a fluid

inlet 19, preferably adjacent the base of the 55 stator.

Mounted within the cylindrical section 9 between the covers 15 is a rotor 20 formed of a central disk 21 fittingly snugly into the cylindrical section, the hub 22 of the disk 60 being keyed to a shaft 23 bearing in the covers 15. Between the periphery of the flange and the hub 22, and to each side of the flange, is a cylindrical section 24 integral with the flange. The edge of each of the 65 cylindrical sections 24 bears against the corresponding cover 15. The disk 21 is provided with impinging blades 25 extending transversely of the blade between the covers 15, and radial of the flange, from the cylindrical sections 24 toward the periphery of the flange. These blades 25 can be made integral with the flange, but, preferably, they are removable from the flange, and are in the shape best shown in Fig. 4. The impinging side 26 of the blade is depressed toward the upper edge of the blade, as shown in 70 24, so that a shoulder 27 is formed on each side of the blade, which is adapted to engage the side of the flange when the blade is forced 75 into position on the flange, and this shoulder being on the opposite side of the impinging face it helps to withstand the thrust of the fluid pressure acting against it. The blade 25 has also at the bottom thereof pins 28 80 adapted to engage corresponding openings in the lateral surface of the corresponding cylindrical section 24, whereby the blade is not only keyed to the flange but to the cylindrical section also, thereby diminishing the 85 possibility of injury to the blade from the thrust thereon by the motive fluid.

It will be noted that the impinging surfaces 26 of each blade 25 are on opposite sides of the blade and are positioned on the 90 opposite sides of the disk 21, so as to receive the motive fluid from opposite directions. For this purpose the lateral surface of the cylindrical section 9 of the stator 8 is provided with two series of nozzles 29 and 30. 100 The series of nozzles 29 is central with one side of the impinging surfaces 26; and the nozzles 30, with the other side of the impinging surfaces of the blades 25. Each of said series of nozzles is provided with the 105 corresponding fluid inlet 19, as previously described. The outlet for the motive fluid, after it has performed its work, is obtained

by providing notches 31 in the edges of the cylindrical sections 24 between the blades 25. The bottoms of said notches are preferably arcuated, the notch being deepest at the non-impinging face of the blade and gradually decreasing in depth as it approaches the following blade, preferably the notch not extending to the following blade. From Fig. 5 it will be seen that the notches 31 on opposite sides of the cylindrical section 24 are directed oppositely. By forming the notches as stated, the motive fluid coming from the nozzles 29 or 30 must first act on the impinging surface 26 of the blade 25, from where it is deflected, and finds an outlet through the notch 31 into the cylindrical section 24. The two cylindrical sections 24 are brought into communication by providing apertures 32 in the disk 21. In one of the covers 15 an outlet 33 is provided, so that the worked motive fluid finds its escape through said outlet 33, whether it comes from one or the other side of the rotor.

In Fig. 7 the turbine is shown with three motive-fluid inlets 19' to each of the annular chambers formed by the annular recesses 12'.

From the foregoing description, taken in connection with the accompanying drawings, the advantage of the construction and operation of the device shown will be readily understood by those skilled in the art to which the invention pertains, and while I have described the principle of operation, together with the device which I now consider to be the best embodiment thereof, I desire to have it understood that the device shown is merely illustrative and that such changes may be made as are within the scope of the appended claims.

Having thus described my invention, I

claim as new and desire to secure by Letters Patent:

1. In a turbine, a rotor comprising a disk, a lateral cylindrical section concentric with said disk and forming a concentric chamber, radial blades above the central chamber extending to the periphery of the disk, said cylindrical section having notches at the edge thereof between the blades. 45

2. In a turbine, a rotor formed of a central disk, tubular sections projecting laterally from each side of said disk, radial blades to each side of said disk above said sections, and openings in said disk establishing communication between the tubular sections at each side of said disk. 55

3. In a reversible turbine, a rotor comprising a disk, radial blades extending to each side of the disk and removable therefrom, 60 each of said blades having a shoulder portion on the opposite sides thereof adapted to engage the sides of the disk substantially as and for the purpose set forth.

4. In a reversible turbine, a rotor comprising a disk, tubular sections projecting laterally from each side of the disk, and radial blades removably associated with said disk and positioned above said tubular sections, each of said blades having a shoulder portion on the opposite side thereof adapted to engage the side of the disk, each of the blades having means adapted to engage the tubular sections substantially as and for the purpose set forth. 75

In testimony whereof I have signed my name to this specification in the presence of two subscribing witnesses.

LUTHER W. GRAYSON.
